PALLETIZED CONTAINER

Arthur H. Thursby, Chicago, Ill., assignor to In-
land Container Corporation, Indianapolis, Ind.,
a corporation

Application January 29, 1949, Serial No. 73,498

5 Claims. (Cl. 229—16)

1

This invention relates to a palletized container. In the packaging industry it has been the custom to individually package a certain product and then package a considerable number of the immediate preceding recited packages in a larger, overall or master container and ship such container to a single consignee. Such master container may weigh as much as 400 pounds which limits its manual handling.

The chief object of the present invention resides in forming the said container so that it can be stacked and readily handled by the so-called fork of a lift truck, with all the attendant advantages resulting therefrom.

The chief feature of the present invention consists in forming integral with a portion of the said container, a plurality of tubular structures adapted to contain reenforcement filler material so that in effect the bottom of the container, is palletized or cleated as it were to accommodate fork tines.

Other objects and features of the invention will be set forth more fully hereinafter.

The full nature of the invention will be understood from the accompanying drawings and the following description and claims:

In the drawings, Fig. 1 is a plan view of a developed blank of a portion of a double bottom form of the container embodying the invention.

Fig. 2 is a perspective view of an inverted covered double bottom cleated container, the cleat filler being shown comprised of accordion type collapsed paper board.

Fig. 3 is an enlarged transverse sectional view through a portion of such container, the cover being omitted since it is not necessarily an essential part of the invention.

Fig. 4 is a perspective view of an end portion of the accordion type filler in slightly extended relation.

Fig. 5 is a perspective view of a rigid, filler element.

In Figs. 1 and 2 of the drawings, 10 indicates a pair of side walls and hinged creased connected therewith are the end walls 11. There is also provided a manufacturers joint 12. Hinge-crease connected to a pair of opposed walls, as for example sides 10, are the bottom forming members 13 which herein are shown of a size or to form a double bottom. They may be of lesser size if desired. Hinge-crease connected to the corresponding edges of the other pair of walls, for example the end walls 11, are the flap portions 14.

Each portion 14 is hinge-creased as at 15, 16, 17 and 18, defining portions 19, 20, 21 and 22 re-

spectively. The box is suitably erected into tubular formation and the flap 12 is stitched to the end wall 11 as at 23. The two bottoms 13 are turned inwardly and lap each other since they are of the size as shown clearly in Figs. 1 and 3, and form an end closure.

Then the flaps 14 are turned inwardly toward each other and the remainder of the portions 19, 20 and 22 are disposed in tubular formation as shown clearly in Fig. 3 and are suitably secured together in such position and to the lapped bottom portions 13 as indicated by stitching 24. This stitching, if used, is applied near each end of the tubes. If adhesive is used it would be coextensive with the tubes. The resulting structure is an open top container having tubular like cleats integral with the bottom or end closure and externally disposed thereon adjacent side edges thereof and substantially coextensive crosswise upon and with the walls to which they are united.

Containers without cleats, of this general type, are usually of corrugated board although the same may be fabricated of solid fibre board as these terms are broadly used in the paper board box industry.

To insure sufficient strength in the palletizing tubes, inserts are provided which in Fig. 5 may comprise a stick of wood or pressed board and of the proper dimensions as to length, width and thickness so as to be slidably receivable when telescopically associated therewith. Such an insert may be held therein by suitable means or held by friction. In Fig. 5 such a solid insert is designated by the numeral 26. Such an insert may comprise individual strips of board. Same may be tape banded if desired.

In Figs. 2 and 4 there is illustrated the preferred form of reenforcing filler 27. It is preferably formed from a single sheet of corrugated board that is of double face character having the two liners 28 and 29 with the intermediate corrugated layer 30. Herein such a board has its corrugated layer cut through at each hinge connection and alternate hinge connections are formed by one liner, the opposite liner being severed in registration therewith, as shown in Fig. 4, so that successive hinge formations fold oppositely and are alternately formed by the two liners 28 and 29. It may comprise a crease-folded structure if desired.

When a sheet of corrugated board is thus slit-hinge fabricated, the same is collapsed from the flat sheet to the position shown in Fig. 4 and then further collapsed to the position shown in Fig. 2. When so collapsed it is telescopically as-

sociated within a tube formation, as previously described, and thus the tube is substantially filled and thus reenforced. The filler tends to expand in the tubular pocket and cling to the walls thereof. Preferably the accordion type is disposed as shown in Fig. 2 although if desired it may be disposed in a position displaced 90° with respect to that shown in FIG. 2.

Herein also the tubes supporting portions 14 are shown suitably secured to the bottom forming walls 13 as by the staples 25. The container so palletized may be provided with any suitable top or cover. In Fig. 2 such a cover is indicated generally by the numeral 31.

It will be obvious, of course, that the tubular pockets thus formed may be disposed closer to the parallel edges of the container or disposed in closer relation to each other, depending upon the position of the first creases #5 in the portions 14 and 19, 20, 21 and 22. Strength disposition and the position of the forks of lifter truck will determine the positions of the cleat constructions.

Whenever the individual load in any container is in excess of that which can be safely accommodated by the two ends disposed cleats, without crushing of the cleats and/or the container, there may be provided an intermediate cleat or cleats, not shown. Each could be formed by a U-shaped member, having the length of the tubular pockets illustrated and a depth corresponding thereto and of any desired width. Such U-shaped pocket forming member may have outwardly and/or inwardly directed flanges suitably secured to and through the two bottom portions 13. The resulting intermediate tubular pocket or pockets would then be filled by a filler structure of the character previously described.

While the invention has been illustrated and described in great detail in the drawings and foregoing description, the same is to be considered as illustrative and not restrictive in character.

The several modifications described herein as well as others which will readily suggest them-

selves to persons skilled in this art, all are considered to be within the broad scope of the invention, reference being had to the appended claims.

The invention claimed is:

1. In a paper board and the like container having four sequentially connected side walls secured together in tubular formation, the combination therewith of end forming flaps, each hingedly connected to the adjacent edge of a wall and foldable inwardly for end closure purposes, at least two of said flaps having creases therein disposed in spaced relation to the hinge connection thereof to form tubes external of and integral with the end closure, the resulting tubes being disposed inwardly of and parallel to the adjacent edge of the container.

2. A paper board container as defined by claim 1 wherein each tube includes a tube reenforcing filler of folded corrugated board.

3. A paper board container as defined by claim 2 wherein the folded corrugated board filler comprises an accordion fold relationship therein.

4. A device as defined by claim 3 wherein the accordion folded filler is of double face board, the faces at opposite sides being alternately slit for successive hinge folds.

5. In a paper board and the like container having four sequentially connected side walls secured together in tubular formation, the combination therewith of end forming flaps, each hingedly connected to the adjacent edge of a wall and foldable inwardly for end closure purposes, at least two of said flaps having creases therein disposed in spaced relation to the hinge connection thereof to form tubes external of and integral with the end closure, the resulting tubes being disposed inwardly of and parallel to the adjacent edge of the container and substantially coextensive in length with the length of that edge.

ARTHUR H. THURSBY.
